Primary Examiner — Christian P. McLean*Assistant Examiner* — Kristopher Michael Blechschmidt(74) *Attorney, Agent, or Firm* — Stetina Brunda Garred and Brucker(57) **CLAIM**

The ornamental design for a hunting tool, as shown and described.

DESCRIPTION

FIG. 1 is a front perspective view of the hunting tool of the present invention showing my new design;

FIG. 2 is a top plan view thereof;

FIG. 3 is a front elevational view thereof;

FIG. 4 is a bottom plan view thereof;

FIG. 5 is a left end view thereof;

FIG. 6 is a right end view thereof; and,

FIG. 7 is a rear elevational view thereof.

The dotted lines shown in the figures form no part of the claimed design.
